UNITED STATES PATENT OFFICE.

WILLIAM SELLERS, OF PHILADELPHIA, PENNSYLVANIA.

IMPROVEMENT IN METAL-PLANING MACHINES.

Specification forming part of Letters Patent No. 36,113, dated August 5, 1862.

To all whom it may concern:

Be it known that I, WILLIAM SELLERS, of the city of Philadelphia and State of Pennsylvania, have invented a new and useful Improvement in Planing-Machines for Metal; and I do hereby declare the following to be a full and exact description of the same, reference being had to the accompanying drawing, and to the figures and letters of reference marked thereon.

The object of my invention is, first, to simplify the construction of planing-machines for metal; second, to provide a more thorough system of bracing the bed between the uprights; third, to impart a smooth and uniform motion to the table upon which is placed the metal to be planed; and, fourth, to place the pulley-shaft so that its axis may be parallel with the line of motion of the table, thus enabling these machines to be placed parallel to lathes and permitting a better arrangement of work-shops.

In all the forms of planers in common use there are motions in common, the principal one of which is the reciprocating motion of the table, and arrangements for lengthening or shortening its stroke. They are all arranged so that the variation of length of stroke can be combined with the adjustment of the general position of the table under the cutting-tool, and the reciprocating motion to the table is usually accomplished in one of three ways, viz: by a chain passing several times around a drum to which it is securely fastened, and having its ends attached to opposite ends of the table, the rotation of the drum giving a rectilinear motion to the table, which will be made in either direction as the motion of the drum is reversed; second, by a screw having its nut attached to the table, the revolution of the screw in either direction producing the desired motion in the table; and, third, the rack-and-pinion motion, in which the rack is attached to the under side of the table, the rotation of the pinion in either direction causing a corresponding movement to the table. This last is probably the one in most common use, and it is this form which my invention is intended to improve.

The nature of my invention consists in furnishing the table with a rack, and in operating this rack, not by the ordinary spur-gearing, but

by a peculiar form of spiral gearing, which enables the driving-shaft to cross the bed diagonally, passing out in a position near enough to the upright to enable the driving-belts to be within reach of the operator.

To describe the machine more particularly, reference may be had to the accompanying drawing, making part of this specification, in which the same letters of reference allude to similar parts throughout the several views, and in which—

Figure 1 represents a side elevation of a planing-machine containing my improvements. Fig. 2 is an end view, partly drawn in section. Fig. 3 is a plan of the machine, with the table removed to show more clearly the parts below same. Fig. 4 is a detached plan of a portion of the table, and Fig. 5 a section of the same through the line 1 2, Fig. 4.

A is the bed of the machine, to opposite side projections of which are bolted the uprights B and B', carrying the cross-head C. The top of the bed A is provided with V-shaped grooves extending its entire length, in which slides the table D, it being provided with downward-projecting ribs *a a* of corresponding bevel to the V-groove. To the under side of the table, and central between the slides *a a*, and extending its entire length, is attached the rack E.

Motion is communicated to the table by means of a spirally-toothed pinion, G, upon a shaft, F, crossing the bed diagonally, (in the manner best seen in Fig. 3,) said pinion G gearing with the rack E. This pinion is in fact a short piece of a coarse screw, the position of the teeth upon the same being as the threads of a screw of a steep pitch and of a like number of threads to that of the teeth in the pinion. The driving-shaft F revolves in bearings *b* and *c* at both ends of the spiral pinion G, which bearings are cast in the bed and connected by a trough, *d*, serving as a receptacle for the lubricating material, in which the pinion G is kept constantly running.

The end of shaft F in the bearing *b* receives a portion of the thrust from the motion of the table under the cut against a step, H, while a portion of the lesser thrust during the return motion of the table is received against the hardened collars *d¹* and *d²* at the other side of G, *d¹* being fastened against the end of bearing *c* and *d²* attached to the shaft F.

The remainder and smaller portion of this thrust is received against the sides of the bearings *b* and *c*. The shaft *F* is, at the end opposite to the step *H*, supported in a third bearing attached to a stand, *I*, and outside of this bearing provided with a bevel-wheel, *J*, which is driven from a pinion, *K*, on the pulley-shaft *L*, the latter having the usual fast pulley *f* and loose pulleys *e* and *e'*, transmitting alternately, by means of an open and crossed belt from the counter-shaft above, the power for the reciprocating movement of the table.

Upon reference to Fig. 4 it will be seen that the position of the teeth in the rack of the table slightly varies from a right angle to the line of motion. This is done to counterbalance the side pressure which would otherwise be produced upon the table by the action of the screw under cut, the degree of variation being equivalent to the coefficient of friction produced by the action of the screw.

The advantages of my improvement as regards facilities for bracing the bed in the parts under strain from the cut will be obvious from reference to Fig. 3. Here it will be seen that the sides of the bed directly between the posts of the uprights *B* and *B'* are firmly braced by a box-shaped connection consisting

of the vertical ribs *i i* and top and bottom plates *j j*, while in the ordinary rack-planer the same space is occupied by the gearing, and in the screw-planer this brace must be much diminished in height to give room for the screw and nut, so that the strengthening of the most vital part of the machine is rendered very difficult. In addition to the above braces, the bearings *b* and *c* of the shaft *F*, united by means of the trough *d*, connect the two sides of the bed in such a manner as to effectually strengthen it to resist the end-thrust of the shaft *F*.

Having thus described my invention, what I claim as new, and desire to secure by Letters Patent, is—

The use of cogged gearing for planing-machines wherein one of the series of cogs has its contact-surfaces formed by straight lines in the direction of its width, while the other series have their contact-surfaces arranged spirally about an axis which is placed at an angle to the line of motion of the first series.
